UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,861**, dated September 2, 1873; application filed August 9, 1873.
[Term of Patent 3½ years.]

R.

To all whom it may concern:

Be it known that I, FREDERICK WINK, of the city and county of Philadelphia, State of Pennsylvania, have invented a Design for Shawl-Pattern, of which the following is a specification:

My design for a striped shawl-pattern is fully illustrated by the accompanying drawing, in which—

Figure 1 is a diagram, showing the relative arrangement of the stripes A and B, of which the pattern is composed; Fig. 2, a view of one-half of the stripe A; and Fig. 3, a view of the stripe B.

The main peculiarities of the stripe A are the central rib *a* and ribs *b* at the edges, each elaborately ornamented by dots, short transverse bars, and diamond-shaped figures. The stripe is otherwise composed of a series of

parallel plain bars or ribs of different widths and shades or colors. The stripe B has a central rib, *d*, of the same character as that of the stripe A, and at either side of the same a series of narrow plain ribs.

Irrespective of the colors employed, I claim—

1. The design for the stripe A, as shown and described.
2. The design for the whole pattern, including the stripes A and B.

In testimony whereof I have signed my name to this specification in the presence of two subscribing witnesses.

FRED. WINK.
